UNITED STATES PATENT OFFICE.

ALFRED J. ENO, OF NEWARK, NEW JERSEY, ASSIGNOR TO THE ALADDIN LAMP COMPANY, OF SAME PLACE.

DESIGN FOR A BICYCLE-LAMP.

SPECIFICATION forming part of Design No. 25,422, dated April 21, 1896.

Application filed March 18, 1896. Serial No. 583,817. Term of patent 7 years.

To all whom it may concern:

Be it known that I, ALFRED J. ENO, a citizen of the United States, residing in the city of Newark, county of Essex, and State of New Jersey, have invented a certain new and original Design for Bicycle-Lamps, of which the following is a specification, reference being had to the accompanying drawings, forming part thereof, in which—

- 10 Figure 1 is a front view of a bicycle-lamp embodying the features of my design, and Fig. 2 is a side view of the same. Figs. 3 and 4 are respectively a top and bottom view of the lamp.
- 15 The leading features of my novel design consist in the novel configuration and ornamentation shown. Thus the main body *a* is cylindrical, having the marginal edge *a'*, which is inwardly curved, as shown, and is ornamented with a series of circular holes *a'* on the opposite sides, as will be clearly evident from an inspection of Figs. 2, 3, and 4. In the opposite sides of the said cylindrical body *a* are the ornamental windows or colored-glass jewels *a*³. At the front of said body is a circular bezel *b*, which has two ornamental beads or rims *b'* and *b*², respectively, and the inwardly curved or concave surface *b*³ between said beads. Said rim *b'* forms the marginal rim or edge of a convex glass front *b*⁴. On the top of said cylindrical body *a* is a cylindrical hood *c*, having its cylindrical surface flaring outwardly, as shown, to be of larger diameter at the top than at the point where
- 20 said cylindrical hood *c* is joined to the cylindrical body *a*. The upper portion of said cylindrical hood *c* is ornamented with perforations *c'* and a cap *c*². Said ornamental cap *c*² has a flat top *c*³ and the marginal edges 45 formed by the several convolutions, which are slightly outwardly inclined, as at *c*⁴, and extending therefrom is a flat surface *c*⁵. From said flat surface *c*⁵ said cap is formed with
- 25
- 30
- 35
- 40

the outwardly and inwardly curved surfaces *c*⁶ and *c*⁷, respectively, and with the vertical surface *c*⁸, from which extends a flat horizontal surface *c*⁹, the outwardly and inwardly curved convolutions *c*¹⁰ and *c*¹¹, and the downwardly-extending surface *c*¹², which is bordered by a ring or bead *c*¹³, all these annular or ring-shaped convolutions forming the ornamental cap, substantially as illustrated in Figs. 1, 2, and 3. In the convolution *c*⁴ of the cap are perforations *c*¹⁴, as clearly represented in said Figs. 1, 2, and 3.

50 The lower surface of the cylindrical body *a* of the lamp is formed with a cylinder *d*, bounded by a marginal rim or bead *d'*, and *e* is the ornamental portion of the oil-receiver of the lamp. Said body *e* has a flat base *e'*, bounded by a vertically-arranged ledge *e*², and is formed with the outwardly-curved cylindrical surfaces *e*³ and *e*⁴, respectively, which meet in the ornamental and outwardly-flaring annular ridge *e*⁵, substantially as set forth, 55 said surfaces *e*³ and *e*⁴ practically forming an ogive.

55 The particular oil-receiver herein shown and described, while of my invention, is not separately claimed herein, as it is obvious that its 60 ornamentation may be varied without changing the general effect of the lamp, the essential features of which are the ornamental main body, its bezel with the lamp, and the hood and cap on the top of said body.

70 Having now described my invention, what I claim is—

75 The design for a bicycle-lamp, substantially as herein shown and described.

In testimony that I claim the invention set forth above I have hereunto set my hand this 14th day of March, 1896.

ALFRED J. ENO.
